Primary Examiner — Sheryl Lane*Assistant Examiner* — Katherine Glennon(74) Attorney, Agent, or Firm — Ladas & Parry LLP(57) CLAIM

The ornamental design for a display screen or portion thereof with graphical user interface, as shown and described.

DESCRIPTION

FIG. 1 is a front view of a display screen or portion thereof with graphical user interface showing our new design; and, FIG. 2 is another front view thereof, as shown in a display screen environment.

The broken lines represent portions of the display and form no part of the claimed design. The dash-dot-dash lines represent boundaries of the claim and form no part of the claimed design.

1 Claim, 2 Drawing Sheets(56)
